DISPENSING CAP

James C. Boyle, Cincinnati, Ohio

Application April 28, 1938, Serial No. 204,835

5 Claims. (Cl. 221—117)

My invention relates to dispensing caps to be placed on containers filled with coffee or relatively fine ground material and which dispenses the material from the container in a meshed 5 quadrant.

It is an object of my invention to provide a dispensing cap which is relatively inexpensive to construct and which dispenses the contents with the greatest of speed and ease.

10 It is a further object of my invention to provide a dispensing cap wherein the amount of material measured and dispensed may be varied.

15 It is a further object of my invention to provide a dispensing cap with all of the above features and in which the relative moving parts are all resilient in contact with each other to prohibit any leakage of the material being dispensed or jamming of the parts.

These and other objects of my invention which 20 will be set forth hereinafter or will be apparent to one skilled in the art upon reading this specification, I accomplish by that certain arrangement and construction of parts of which I shall now describe an exemplary embodiment. Reference is now made to the drawing which forms 25 a part hereof, and in which:

Figure 1 is a front elevation of my dispensing cap mounted on a container.

Fig. 2 is a plan section with parts cut-out of 30 my dispensing cap taken on section line 2—2 of Fig. 1.

Fig. 3 is a vertical section of my dispensing cap taken on the section line 3—3 of Fig. 2.

Fig. 4 is another vertical section of my dispensing cap taken on the section line 4—4 of 35 Fig. 2.

Fig. 5 is a perspective of a bottom plate of my dispensing cap.

Fig. 6 is a perspective view with parts broken 40 away showing the bottom portions of the compartments of my dispensing cap.

Fig. 7 is a perspective with portions broken away showing the top part of the compartments of any dispensing cap.

45 Briefly in the practice of my invention, I provide a dispensing cap comprising two substantially opposed compartments joined together by a blank web and closed at the top by a circular panel having an opening registerable with the compartments.

50 The lower portions of the compartments are formed by a separate casting which is telescopic on the upper part and is urged therefrom by a spring. There is a lower closure panel having an opening registerable with the bottom of the compartments and with the opening substantially opposed in the opening of the upper panel. These two panels are also urged apart by a spring and are rotatable upon a telescoping axis 55 together. The spring urges the two telescopic

castings of the compartments apart and at the same time forces them against the upper and lower panel, thus insuring a resilient pressure at all times between both panels and the castings against which they bear. An adjusting screw limits the expansion of the telescoping axis and thus, by adjusting the same the depth of the compartments may be varied.

Referring to the drawing, I provide a casting 1, which terminates in two substantially opposed 10 compartments 2 which in my exemplary embodiment are substantially in the form of a quadrant. These compartments 2 are joined together by blank webs which are also in the form of quadrants. There is a hollow hub 4, having an annular opening 5, in its center and with its skirt 6 running down to the bottom of the compartments 2 in the casting 1.

Telescoped on the annular portions 7 of the casting 1, I provide a second casting 8 having 20 an annular rim 8a which defines by cross straps 9, four quadrants substantially the same size and shape of the quadrants 3 and 2. Two substantially opposed quadrants 2a are left opened while the other quadrants are closed by webs 3a. There 25 are slots 10, in the skirt 6 of the hub 4 which permit the insertion of the straps 9 of the lower casting 8. The annular rim 8a of the casting 8 is substantially greater and telescopic about the annular rim 7 of the casting 1. There is a hollow hub 11 centrally located amongst the quadrants 3 of the casting 8, and of smaller diameter and telescopically within the skirt 6 of the hub 4.

The lower casting 8 is telescoped up into the upper casting 1, as is indicated in Figs. 3 and 4 and in such a manner that the quadrants 2a form the lower part of the compartments 2. Within the hub 11 and seating against its innerface 12 is a spring 13. The other end of this spring seats within the hub 4's upper face and thus tends to urge the castings 1 and 8 apart.

There is an upper closure plate 14 having a central hub 15 which rides over the hub 4 and which closes the top of the compartments 2. The plate 14 has an opening of quadrant width 45 and registerable with the tops of the compartments 2. Integrally with the plate 14 and projecting downwardly through the hub 4 is a square stem 16.

I provide a lower closure plate 17 in the form 50 of a circle, of a diameter substantially the same as the annular rim 8a. There is an opening 18 in the form of a quadrant in the plate 17 and I preferably provide a downwardly projecting chute 19 surrounding a portion of the opening 55 18. The lower plate 17 has an upwardly projecting stem 20 with a square cut-out portion 21 running longitudinally therethrough. The square stem 16 fits within the square hole 21 and thus the stems 16 and 20 will rotate together and are 60

axially slidable within each other. The plate 17 is mounted on the bottom of the casting 8 as indicated in Figs. 3 and 4 with the stem 20 projecting up through the hub 11 and within the coils of the spring 13. In assembly, the stems 16 and 20 are so positioned as to place the opening 18 in the lower plate, opposed to and substantially from the opening, in the upper plate.

The bolt 22 pierces the plate 17 and is screwed 10 into the end of the square stem 16. There is an adjusting nut 23 on the bolt 22 which varies the expanding limitations, to which the plates 17 and 14 may be moved.

In my exemplary embodiment, I have provided 15 a groove 25 in the lower rim 8a of the casting 8 in which fits an upstanding rim 26 around the periphery of the plate 17. I also provide the plate 17 with a radially projecting handle 27 and preferably with a thumb guard or stop 28.

20 When the upper casting 1 and the lower casting 8 are telescoped and the plates 17 and 4 placed in position with the spring 13, within the hubs 11 and 14, it is apparent that the spring 13 urges the castings 1 and 8 apart by forcing them 25 against the lower plate 17 and the upper plate 14. This insures a resilient contact at all times between the plates and the castings.

From the above construction, it is apparent 30 that when the opening in the upper plate is registering with one compartment 2, the opening 18, in the lower plate is registered with the bottom of the substantially opposed compartment and the solid portions of the plate 14 covers the top of the compartment 2, which is over the opening 18. It is also apparent at this time, that in 35 this position the solid portion of the plate 17 covers the compartment 2 which is opened at the top. Due to the fact that the connecting webs 3 are at least as great in size as the size of the 40 compartments 2, the rotation of the plates 14 and 17 together will never provide at one time, a compartment 2 with an opening above and an opening below at the same time.

In order to prevent the material in the 45 container riding around on the upper plate 14, I have provided a vane 29 which almost contacts the upper portion of the plate 14 and is terminated at its center with the other terminal held in position on the casting 1 by means of fingers 50 30. I also provide an upstanding rod 31 which rides around with the upper plate 14.

From the above description it is apparent that 55 due to the telescoping feature of the castings 1 and 8, and inasmuch as these castings together define the depth of the compartments 2 and hence their capacity, that the axial or telescoping movement of the two castings will vary the capacity of the compartments 2. I, therefore, provide a scale 30 on the outside of the annular 60 portion 7 of the casting 1 which indicate the relative movement of the two castings 1 and 8, and hence, the relative contents of the compartments 2.

It is, therefore, understood that different forms 65 of my preferred form may be made without departing from the spirit of my invention.

Having thus described my invention, what I claim as new and desire to secure by Letters Patent is:

70 1. A dispenser cap comprising at least two

compartments of a given peripheral configuration and size, said compartments being spaced apart by a blank web at least as large as the peripheral configuration of the compartments, an upper and lower closure for said compartments 5 comprising plates, at least one opening in each plate of a peripheral configuration as great as that of the compartments, the opening in one plate being registered with one compartment while the opening in the other plate is registered 10 with the other compartment and means for moving said plates together so that their openings will register with successive compartments, the depth of said compartments being adjustably variable. 15

2. A dispenser cap comprising two oppositely disposed substantially sectorial compartments at least as small as a quadrant and having a depth and being spaced apart by oppositely disposed substantially sectorial webs, an upper and lower 20 closure for said compartments comprising circular plates mounted on and rotatable by a common shaft, an opening in each of said plates of a configuration registerable with said compartments, the opening in one plate being oppositely disposed 25 to the opening in the other plate, means for rotating said shaft and stops co-acting therewith to position said plates so that the openings are in registry with said compartments, the depth of said compartments being adjustably variable. 30

3. A dispenser cap comprising two oppositely disposed substantially sectorial compartments at least as small as a quadrant and having a depth and being spaced apart by oppositely disposed substantially sectorial webs, an upper and lower 35 closure for said compartments comprising circular plates mounted on and rotatable by a common shaft, an opening in each of said plates of a configuration registerable with said compartments, the opening in one plate being oppositely disposed 40 to the opening in the other plate, means for rotating said shaft and stops co-acting therewith to position said plates so that the openings are in registry with said compartments, the depth of said compartments being adjustably variable, the 45 opening in said lower plate having a chute depending therefrom.

4. A dispenser cap comprising two oppositely disposed substantially sectorial compartments at least as small as a quadrant and having a depth 50 and being spaced apart by oppositely disposed substantially sectorial webs, an upper and lower closure for said compartments comprising circular plates mounted on and rotatable by a common shaft, an opening in each of said plates of a configuration registerable with said compartments, the opening in one plate being oppositely disposed 55 to the opening in the other plate, means for rotating said shaft and stops co-acting therewith to position said plates so that the openings are 60 in registry with said compartments, said rotating means comprising a projecting tongue on the lower plate.

5. A dispenser cap comprising compartments 65 of a given peripheral size divided by walls, loading and dumping means for said compartments associated therewith, said compartments and walls being variably adjustable as to depth by a single means.

JAMES C. BOYLE. 70
